(57) **CLAIM**

The ornamental design for a decorated invertible interactive toy house, as shown and described.

DESCRIPTION

FIG. 1 is a perspective view of the invertible interactive toy house of this invention folded to expose the exterior walls thereof;

FIG. 2 is a front elevation view of the decorated invertible interactive toy house of FIG. 1;

FIG. 3 is a rear elevation view of the decorated invertible interactive toy house of FIG. 1, the right side and left side views being identical;

FIG. 4 is a top plan view of the decorated invertible interactive toy house of FIG. 1;

FIG. 5 is a bottom plan view of the decorated invertible interactive toy house of FIG. 1;

FIG. 6 is a layout of the decorated invertible interactive toy house of FIG. 1 unassembled and laid out flat and showing the exterior walls thereof;

FIG. 7 is a layout of the invertible interactive toy house of this invention unassembled and laid out flat and showing the interior walls thereof;

FIG. 8 is a perspective view of the invertible interactive toy house of this invention folded to expose the interior walls thereof;

FIG. 9 is a front elevation view of the decorated invertible interactive toy house of FIG. 8;

FIG. 10 is a right-side elevation view of the decorated invertible interactive toy house of FIG. 8;

FIG. 11 is a rear-side elevation view of the decorated invertible interactive toy house of FIG. 8;

FIG. 12 is a left-side elevation view of the decorated invertible interactive toy house of FIG. 8;

FIG. 13 is a top plan view of the decorated invertible interactive toy house of FIG. 8; and,

FIG. 14 is a bottom view of the decorated invertible interactive toy house of FIG. 8.
